Primary Examiner — Prabhakar Deshmukh(74) *Attorney, Agent, or Firm* — E. Victor Indiana; Indiana & McConnell, LLC(57) **CLAIM**

The ornamental design for a audio input/output device, as shown and described.

DESCRIPTION

FIG. 1 is a front side oriented perspective view of audio input/output device showing our new design;

FIG. 2 is a rear side oriented perspective view of the audio input/output device of FIG. 1;

FIG. 3 is a left side view of the audio input/output device of FIG. 1;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines illustrate environment and forms no part of the claimed design.
